UNITED STATES PATENT OFFICE

LAWRENCE H. OFFUTT, OF RASPEBURG, MARYLAND, ASSIGNOR TO THE D. R. S. COMPANY, INC., OF BALTIMORE, MARYLAND

DEVICE FOR EXTINGUISHING FIRE ON CIGARETTES

Application filed April 20, 1929. Serial No. 356,731.

This invention relates to a device to be used in connection with ash trays or other ash receptacles, for extinguishing the fire on cigarettes or the like so that the objectionable smoke from burning cigarette stumps, will be eliminated.

An important object of the invention is to provide a device of this character which may be positioned over one edge of an ash tray or receptacle and held in place by its frictional contact with the tray or receptacle.

A still further object of the invention is to provide an extinguisher of this character including flexible arms between which the lighted end of a cigarette may be passed to extinguish the fire.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a fragmental plan view illustrating a device constructed in accordance with the invention positioned on an ash tray.

Figure 2 is a sectional view taken on line 2-2 of Figure 1.

Figure 3 is a fragmental plan view illustrating a modified form of the invention.

Figure 4 is a sectional view taken on line 4-4 of Figure 3.

Figure 5 is a further modified form of the invention.

Referring to the drawings in detail, the reference character 5 designates an ash tray which in the present showing is in the form of a dish, however it is to be understood that the device forming the subject matter of this invention is so constructed that it may be readily positioned over an edge of an ash tray or ash receptacle, of any suitable construction.

The extinguisher comprises a length of sheet metal having a portion of one end thereof of cut away defining fingers 6 which are bent

inwardly as clearly shown by Figure 2 of the drawings so that they will engage the edge of the tray or receptacle to which the device is secured.

The opposite end of the length of sheet metal is cut away throughout the greater portion of the length of the sheet material providing lateral fingers 7 which are bent so that the side faces thereof will be disposed in substantially parallel spaced relation with each other presenting wide surfaces between which a cigarette may be passed to extinguish the fire thereof.

As clearly shown by Figure 2, a portion of the length of sheet metal extends downwardly as at 8 where it contacts with the side of the tray or receptacle to hold the fingers 7 spaced from the tray, so that the ashes from the cigarette of which the fire is being extinguished, may fall clear of the fingers 7.

In the form of the invention as shown by Figures 3 and 4 of the drawings the device comprises a length of sheet metal having one end thereof bent rearwardly in spaced relation with the body portion or length of sheet metal, as clearly shown by Figure 4, the free end of this rearwardly bent portion which is indicated by the reference character 9, extends outwardly as at 10, so that it may be readily positioned over one edge of a supporting tray.

The body portion of the device is indicated by the reference character 11 which cooperates with the section 9 in clamping the side of the tray. Fingers 12 form a part of the device, and are substantially wide presenting wide surfaces to contact with the cigarette passed through the device, to extinguish the fire thereof.

These fingers 12 curve slightly outwardly so that they will release the cigarette held therein when another cigarette is forced between the fingers.

A tongue 13 extends forwardly from the body portion and is designed to rest on the bottom of the tray, which is indicated by the reference character 14, to hold the device against bending downwardly when a cigarette is forced between the fingers.

As shown by Figure 5, the cigarette fire ex-

tinguisher is constructed for use in connection with match boxes, the match box being indicated by the reference character 15 and the cigarette fire extinguisher being indicated 5 by the reference character 16. The cigarette fire extinguisher in the form of the invention is provided with a substantially long flange 17 which is spaced from the fingers 18 and disposed in parallel relation with the rear 10 edges thereof, so that the fingers 16 will be supported adjacent to the side of the match box and parallel therewith.

I claim:

15 A cigarette fire extinguisher comprising a body portion formed of a length of sheet metal having a downwardly extended portion to overlie the edge of an ash tray, gripping fingers formed on the body portion and adapted to grip the edge of the tray on which 20 the device is positioned, yieldable fingers forming a part of the body portion, the yieldable fingers being disposed in spaced relation with each other, and the outer edges of the yieldable fingers being free and exposed 25 to permit a cigarette to be drawn between the fingers throughout the lengths of the fingers.

In testimony that I claim the foregoing as my own, I have hereto affixed my signature.
